(57) **CLAIM**

The ornamental design for a combined wireless speaker and range extender device, as shown and described.

DESCRIPTION

FIG. 1 is a top, front, right-side perspective view of a combined wireless speaker and range extender device; FIG. 2 is a bottom, front, left-side perspective view thereof; FIG. 3 is a top, back, right-side perspective view thereof; FIG. 4 is a front view thereof; FIG. 5 is a back view thereof; FIG. 6 is a left-side view thereof; FIG. 7 is a right-side view thereof; FIG. 8 is a top view thereof; and, FIG. 9 is a bottom view thereof.

The dashed broken lines depict portions of the combined wireless speaker and range extender device that form no part of the claimed design. The crosshatched pattern is a mesh fabric and is understood to be distributed uniformly over the surface of the claimed design upon which the pattern occurs.
